UNITED STATES PATENT OFFICE.

GEORGE W. DAY, OF HAVERHILL, MASSACHUSETTS, ASSIGNOR, BY DIRECT AND MESNE ASSIGNMENTS, TO WALTER SHAW, TRUSTEE, OF BOSTON, MASSACHUSETTS.

MACHINE FOR DRIVING STAPLES.

SPECIFICATION forming part of Letters Patent No. 558,013, dated April 7, 1896.

Application filed July 23, 1888. Serial No. 280,755. (No model.)

To all whom it may concern:

Be it known that I, GEORGE W. DAY, of Haverhill, in the county of Essex, and in the State of Massachusetts, have invented certain new and useful Improvements in Machines for Driving Staples; and I do hereby declare that the following is a full, clear, and exact description thereof, reference being had to the accompanying drawings, in which—

- 10 Figure 1 shows a view of my machine in side elevation; Fig. 2, a view of the same in front elevation; Fig. 3, a detail enlarged view, in side elevation, of the staple-driving mechanism; Fig. 4, a similar view from the other side of the machine, showing the means for taking the staples from the hopper; Fig. 5, a detail plan view of the mechanism shown in Fig. 3; Fig. 6, a detail view, partly in section and partly in side elevation, showing the 15 mechanism for feeding the staples to the plunger or hammer; Fig. 7, a detail view of a section on line xx of Fig. 6; Fig. 8, a detail view of the channel-guide and adjusting mechanism therefor; Fig. 9, a view of a section on line yy of Fig. 6; Fig. 10, an enlarged detail view showing the operation of the picker for taking the staples from the hopper; Fig. 11, a plan view of the anvil-block on the horn; Fig. 12, a view of a section of the same on 20 line zz of Fig. 11; Fig. 13, a view of a vertical section of the upper guide for the plunger; Fig. 14, a cross-sectional view of the picker; Fig. 15, a detail perspective view of the mechanism for operating the picker; and Fig. 16, a detail view, partly in section and partly in elevation, showing the lower portion of the staple receiving and holding plate and the inclined staple-engaging face beside the hammer-bar way.

- 30 Letters of like name and kind refer to like parts in each of the figures.

The object of my invention is to provide certain improvements in machines for driving staples applicable to the fastening of the soles of boots and shoes and for other purposes; and to this end my invention consists in the machine and in the construction, arrangement, and combination of the parts thereof, as hereinafter specified.

- 35 In carrying out my invention it has been

my special intention to provide a machine containing not only mechanism adapted to best drive the staples or double-pointed tacks delivered to the hammer or driving device, but also mechanisms or devices for automatically taking the staples from a suitable hopper or receptacle and feeding and delivering them in proper position to such hammer or device.

40 I shall show and describe my machine as operated by a treadle; but I do not limit myself to such means for moving or causing the mechanism to move.

45 If desired, the machine can be connected with any desired source of power in such way as to cause it to be operated continuously, as long as required, or intermittently upon the shifting of a suitable clutch or starting lever.

50 While I shall show and describe my machine as arranged for driving staples or double-pointed tacks, I desire it to be understood that it can be employed also for the driving of other forms of tacks or fasteners.

55 Obviously the magnetic hammer-bar with the inclosing and guiding way can, without departure from my invention, be used to drive single as well as double pointed tacks, the only change required being one of form to suit the tack supplied to the hammer-bar.

60 In the drawings, A designates the support-frame or standard for supporting the various operative parts of the machine. As shown, this frame is made hollow for the passage of the treadle-rod B; but such construction is not necessary. Pivoted in the lower portion of the frame or standard is the treadle 65

portion of the frame or standard is the treadle C, pivotally connected at its inner end to the lower end of rod B and on its outer end provided with a suitable foot-piece of the usual form and construction. The upper end of the treadle-connecting rod B passes up through an opening in the top of the main upright portion of the frame. Passing through and guided in another opening in the frame in front of the rod B is the stem or shank D of the horn E for supporting the boot or shoe sole while the staples are being driven into it. This horn is of the usual and well-known construction of such device in use in boot and shoe machines, except that it is provided 70

with a die or anvil of a peculiar form and construction adapted to clench the staples in a manner to be described hereinafter.

The upper portion of the horn-shank D is guided, as described, in a suitable opening in the frame-standard, while its lower end projects down through and is guided in an opening in the bracket or fixed arm A' within said standard. On this shank is a collar D', preferably, as shown, fixed in place by means of a set-screw d. Surrounding the horn-shank is the spiral spring D², engaging with its upper end the fixed collar D' and with its lower end the sliding collar D³, made movable on said shank. A fork B', attached to and carried by the treadle-rod B, engages the under side of this sliding collar with its fork-arms, which project forward between the collar and the horn-shank-guiding bracket or arm A' on the frame-standard. Besides engaging the collar D³, so as to raise it when the treadle-rod B is raised, this fork also serves as a stop to limit the downward movement of the rod by coming in contact with the upper side of said frame arm or bracket A'.

The fixed collar D' is so situated on the horn-shank D as to be, when the horn is down, some distance below the point where the shank passes through the top of the frame-standard. This construction and arrangement is to allow the horn-shank and horn to rise a certain distance, for a purpose to be described hereinafter. If desired, an elastic or semielastic washer d' can be placed between the shoulder at the lower end of the horn E and the top of the frame-standard to take up any shock and prevent noise when the horn descends after being raised.

With the construction set forth when the treadle is operated to raise rod B the horn E will, through the fork B', collar D³, spring D², fixed collar D', and shank D, be raised, and as long as the rod B remains elevated the horn will be held in its raised position by the stress of the spring D², compressed between the sliding collar D³ and the fixed collar D', by the action of the fork B' on rod B, engaging the sliding collar. With the treadle-rod raised, the horn will then be capable of a certain amount of yielding to a downward blow or pressure on the top of the horn. This yielding, which is provided for by the spring D², is for a purpose that will be explained hereinafter. When the treadle is released, the spring will, through the sliding collar and the rod-fork engaged thereby, tend to return the treadle-rod and treadle to their first positions again, and the horn will drop until the shoulder at its lower end rests again upon the top of the frame-standard or the cushion-washer thereon.

The top of the horn E can be of any desired shape or be provided with any desired form of anvil; but I prefer to provide it with the anvil E', (illustrated best in Figs. 11 and 12,) having its upper face formed with an annular concavity or groove. As seen in cross-

section, this groove has its sides beveled or made inclined, the bevel or incline being preferably a concave one. The annular groove is of such diameter that the lower ends of the two legs of a staple to be used can be in contact at the same time with inward and downward inclines at opposite outer sides of the groove. This arrangement is to secure a simultaneous inturning and clenching of the staple ends when the staple is driven down against the anvil.

Projecting up from the frame-standard A is the upright A², which can be cast in one piece with said standard or made separate and bolted or otherwise fastened thereto. Sliding vertically at one side of this upright A² is the bar G, guided in its reciprocations by means of the guide-blocks G' G² engaging slots g g in the bar. Screws G² G³, passing through the guide-blocks and tapped into the upright, hold the blocks in place and, by means of their heads overlapping the sides of the respective slots, serve to keep the bar securely in place, while leaving it free to slide. At or near its lower end the bar G is provided with a forwardly-projecting lug or arm G³, to which is screwed or otherwise fastened the upper end of the treadle-rod D.

I do not limit myself to the particular means shown and described for holding and guiding the bar G in its movements. Any other of the well-known forms and constructions of guiding devices for reciprocating bars or pieces can be used without departing at all from the spirit of my invention.

In a portion of bar G, at the rear side thereof, is a vertical slot g' for receiving the adjustable pins g² g³. Each of these pins has a head projecting out beyond the side of the bar and overlapping the front and rear edges of the slot g'. The other end of each pin is threaded and screwed into a plate or nut g³ overlapping the sides of the slot on the inner side of the bar. With this construction, when the pins have been adjusted, as desired, along the slot g', they can be fixed as adjusted by screwing them in so as to clamp portions of the bar firmly between the pin-heads and the respective nuts. Projecting between these pins is an arm of the lever H pivoted to the upright A² at h. The pins form adjustable abutments or blocks adapted to strike the lever-arm and move the lever, as the bar G nears the limits of its movement in opposite directions, and to leave the lever without movement while the bar is moving over the middle portion of its travel. A pin G⁴, fixed to the bar G, projects therefrom through a slot in the upright A² to a point beyond the other side of the latter.

Upon an arm A³, extending upwardly and forwardly from the upright A², is the guide for the hammer or driving-plunger situated vertically over the upper anvil-bearing end of the horn E.

The hammer or plunger head I consists of a bar of steel, permanently magnetized, which

is guided and slides in a groove k in a vertical plate or block K, of brass or other non-magnetic material. A plate K', also of non-magnetic metal or material, preferably brass, 5 engaging the bar I on the side not in contact with plate K, serves to keep the bar in place in the groove k . The brass plate K', which thus completes the inclosure of the vertical way for the reciprocating magnet-bar I, is 10 shown as fastened in a groove or rabbet in the front vertical face of the arm A³ of the upright A² by means of screws. I do not, however, limit myself to such an arrangement or such means of fixing the plate K' in place. 15 All that is necessary is that the magnet-bar I, forming the hammer-head, shall be guided vertically and that its guideway shall be inclosed by or made of non-magnetic metal or material. The magnet-bar I is at its upper 20 end clamped and held in a slot i' in the end of the plunger I' by means of screws i^2 i^2 . The extreme lower end or head of this plunger is enlarged, as shown, and is provided with a rearwardly-extending guide-arm 25 I², engaging a vertical guide-slot L in the upright guide-bar L', fastened at its lower end to the arm A³ of the frame-upright A². A second guide-bar L², parallel with and in front of bar L', is also supported at its lower 30 end from arm A³. Any desired means or method of supporting and holding these guide-bars in place can be used.

As shown, the lower ends of the rear and front bars are respectively clamped against 35 a vertical piece on arm A³ and the front side of plate K by means of two bolts L³ L³, passing through the guide-bar ends, the plate K, and the piece on arm A³. With this construction these bolts serve the double purpose 40 of fastening the lower ends of the guide-bars and holding the brass plate K in place to properly guide the magnet-bar I in its way.

Between the upper ends of guide-bars L' L² the block L⁴ is clamped by means of the 45 two bolts passing through the block and bar ends. Tapped down through a hole in block L⁴ is the hollow externally-threaded screw L⁵, through which passes the upper end of the stem or shank of the magnet-bar carrying 50 plunger I'. A lock-nut L⁶ is provided on this screw above the block L⁴ to lock the screw from turning when it has been adjusted up or down to raise or lower its lower end. Surrounding the stem or shank between the end 55 of screw L⁵ and the enlargement or head at the lower end of the plunger-shank is a spiral spring I⁴. The stress of this spring in its downward pressure on said enlargement or head, and so the force with which it will 60 drive the plunger and magnet-bar downward when they have been elevated, can be adjusted at will by loosening the locking-nut L⁶ and turning the screw up or down. The guide-arm I² on the plunger engaging the slot 65 L in the rear guide-bar L' serves to prevent any twisting or rotation of the plunger to

cause binding of the magnet-bar I in its guideway.

To take up shock and deaden any noise caused by the descent of the plunger I contemplate placing at L⁷ one or more cushions of rubber resting on the top of the guide-head through which the magnet-bar passes in position to receive the lower end or face of the enlargement on the plunger. 75

To raise the plunger and magnet-bar of the hammer against the stress of the spring I⁴ and then release them, so that they will be driven down again by the spring to deliver a blow to drive a staple, I prefer the means and 80 mechanism shown best in Figs. 1 and 3.

Pivoted to the upper end of the sliding bar G, which is connected with the treadle-rod D, as hereinbefore described, is the pawl-lever M, provided with the shoulder m to engage 85 the under side of the arm I² on the plunger. This shoulder is so situated that when the sliding bar G and the pawl-lever are down in their lowest positions it is free to be moved in under the end of arm I² by a forward swing- 90 ing of the pawl-lever M upon its pivotal connection with sliding bar G.

The upper end of the pawl-lever projects up between guide-lugs M' M' on the rear guide-bar L'. A spring M² engaging the rear side 95 of the upper end of the pawl-lever tends to force the same forward. On the forward side of the pawl-lever, above the shoulder or lug m , is an incline m' , adapted, as the pawl-lever is raised, to come in contact with the tripping 100 pin or bolt M³, so as to cause a rearward swing of the pawl-lever sufficient to disengage the shoulder m from the arm I² as the sliding bar G and the pawl-lever reach the limit of their upward movement. On the pawl-lever below 105 the lug or shoulder m is an upward and forward incline, adapted to engage the end of arm I² when the plunger is down and the pawl-lever is being lowered. This incline or cam will cause the pawl-lever to swing rearward 110 until the shoulder m passes below the arm I², when the spring M² will swing the pawl-lever quickly forward to bring said shoulder under and in engagement with the plunger-arm. 115

In order to insure a full upward movement of the sliding bar G, the pawl-lever, and the plunger before such parts can descend again and to hold them from descent, as desired, when only partially raised by movement of the treadle and treadle-rod, I provide the rear 120 side of the sliding bar G with a series of ratchet-reeth O O to be engaged by the nose of pawl O', pivoted at O² to the frame-upright A². A spring O³ presses up against the lower end of this pawl, which is so shaped that the 125 pressure of the spring will tend to hold the pawl as swung into position to engage the teeth O or to stand clear of them. This object I attain by providing the lower end of the pawl with a projection or edge so situated that when the pawl is swung forward to 130 engage the ratchet-teeth the line of upward

pressure of the spring will be to the rear of the pawl-pivot. When the pawl is swung back away from the teeth O , the forward movement of its lower end brings the line of pressure of the spring in line with or slightly to the front of the pivotal point of the pawl. The one spring then serves to hold the pawl yieldingly in position to properly engage the ratchet-teeth and to retain it away from the teeth when it has been swung out of engaging position. A cam-lug O^4 on the sliding bar G below the ratchet-teeth serves to engage the upper end of the pawl and carry it rearward as the bar reaches the limit of its upward movement. The lower side of the lug O^4 is made abrupt and is in position to engage a stop-screw O^5 on the short arm O' on the pawl as the bar G reaches the lower limit of its motion, so as to swing the pawl forward again into position to engage the ratchet-teeth O .

The way in which the magnet-bar I forming the hammer-head fits and slides is of such size and shape as just to allow the free passage up and down within it of one of the staples to be used—that is, the way is of a width equal to or slightly greater than the width of one of the staples between the outer sides of its opposite legs and is of a depth equal to or slightly greater than the thickness of the staple. With this construction a staple clinging by its top to the lower end of the magnet-bar can rise and fall in the way as the magnet-bar is raised and lowered, and will, by the walls of the way, be held and guided in a vertical position with the points of its legs downward in line with the said hammer-bar. If then an iron or steel staple be fed to the magnet-bar in such position that its top or head shall be attracted and held to the lower end of the bar by the action of the magnetism in the latter, the staple will be drawn up within the magnet-bar way as the bar rises and will be retained in position on the bar end to be driven by the descent of the bar straight into a shoe-sole or other object held below the lower end of the barway.

In order to automatically feed the staples in proper position to the magnet-bar, so that each time the bar rises it will take a staple with it ready to be driven by the fall of the bar, I have provided the following feed mechanism: Attached to and carried by a slide P , having a slot P' , engaging a guide-block P^2 , fastened to the side of upright A^2 , is the hopper R for receiving and containing a supply of staples. The screws p , which fasten the guide-block in position, also serve, by means of their heads overlapping the sides of slot P' , to retain the slide on the block.

As indicated hereinbefore, the staples to be used should be made of metal adapted to be attracted by the magnet-bar as the ordinary iron or steel staples or double-pointed tacks now in the market. The hopper R is, as shown, divided within into chambers by a transverse upwardly-extending partition R' .

In this partition, which is preferably curved or inclined toward the forward side of the hopper, is a slot R^2 , whose lower portion is of a width about equal to the width of the space between the legs of one of the staples, but not as great as the extreme width of the tack. The upper portion of the slot is enlarged, so as to have a width equal to or a trifle greater than the extreme width of a staple between the outer sides of its legs. The forward side or end of the hopper is likewise provided with a similarly formed and shaped slot in line with that in partition R' . For a reason which will appear hereinafter the narrow portion of the slot in the hopper end is not as long and does not extend up as high as the corresponding portion of the slot in partition R' .

The supply of staples or double-pointed tacks is placed directly in the rear chamber or compartment of the hopper, as indicated best in Figs. 6 and 10. The lever H , intermittently actuated, as hereinbefore described, by the movements of bar G , is connected with the hopper-carrying slide p by means of a pin p' on the slide engaging a fork on an arm of the lever. Extending forwardly and downwardly within or along the arm A^3 on upright A^2 , and at its forward end opening into the magnet-bar guideway near the lower end thereof, is the way or passage down which the staples are fed to the bar. Within this feedway is the forwardly and downwardly inclined plate S , turned up on edge, so as to receive the staples astride of its upper edge and of such thickness as to hold the staples steady while leaving them free to slide down of their own gravity toward the lower end of the plate. This end of the staple-receiving plate is, as shown, flush with the inner or rear side of the magnet-bar guideway, so that with the staples left free to slide down the plate the lowest or end staple will, when the magnet-bar is down, rest directly against the rear side of the bar. The plate is to be made of brass or other non-magnetic metal or material, in order that no magnetism of it may interfere with the downward sliding of the staples. Situated above plate S is a bar or plate S' , also of brass or non-magnetic material, having its lower side parallel with the upper edge of the plate S and at such distance therefrom as to just leave space for the travel of the tops of the staples down along the plate-top. This bar will then, while not interfering with the sliding of the staples downward and forward toward the hammer-magnet, serve as a guide to keep the staples down in proper position astride of the plate edge. Pivoted to ears s on the upper end of plate S is the swinging plate S^2 , whose upper edge, when the plate is swung up, comes into line with and forms a continuation of the upper edge of plate S , as indicated in Fig. 10. With the pivotal point of the swinging plate below its upper edge, the ends of the two plates at their upper edges can be employed as stops to limit the upward swing of plate S^2 when the edge of such plate has been

brought into line with the top of the fixed plate. The rear or outer end of plate S^2 , which is of the same thickness as plate S , so as to readily receive staples astride of it and allow them to slide freely along it when the plate is tipped up, is in position to project into the hopper R , through the vertical slots in the hopper end and partition R' . Toward its outer end the plate is cut away underneath, so as to provide a point at the extreme plate end adapted, if the plate be thrust into a mass of staples, to most readily pass between the legs of one or more of the staples.

Attached to the plate S^2 is a lug s' , supporting the bar S^3 above and parallel with the upper plate edge. Such bar, like bar S' above plate S , serves to keep any staples astride of the upper edge of plate S^2 down in proper position while leaving them free to move or slide along the plate. At its forward end this bar S^3 projects beyond the end of plate S^2 , so as to overlap the upper edge of the rear portion of plate S when the swinging plate S^2 has been swung up. The lower side of the bar then is in line with the under side of guide-bar S' and forms therewith a continuous guiding-surface to keep the staples down in place as they slide forward and downward toward the hammer-bar. The rear end of the bar S^3 , which does not project back to the point of plate S^2 , is turned or inclined upward and rearward away from the top of the plate.

Pivoted to frame-upright A^2 on the opposite side from bar G and lever H is the lever T , provided with a fork t on one arm engaging the pin G^4 on the bar G already described herein. Carried by the upwardly-extending arm of lever T is the rearwardly-extending curved bar T' . The upper edge of this bar is, along its rear portion, curved substantially on the arc of a circle struck from the pivot of lever T as a center. From this portion concentric with the swing of the lever the upper bar edge is formed on an eccentric downward and inward curve approaching nearer and nearer to the pivotal center of the lever T . This eccentrically-curved portion of the bar is provided with the series of teeth or inclined-faced projections $t' t'$. On the side of swinging plate S^2 , in position to be engaged by the upper edge of bar T' , is the pin or stud t^2 , having its under bar-engaging side preferably made wedge-shaped or with oppositely-inclined faces, as shown. The radius of the swing of the lever T and of the concentric portion of the upper curved edge of the bar T' is of such length that when, by the movement of the lever, this concentric portion of the bar is brought under and into engagement with the stud or pin t^2 the plate will be swung up into its uppermost position with its upper edge in line with the corresponding edge of plate S . As the lever is swung forward to bring the downwardly-curved portion of the bar edge under the pin or stud t^2 the plate S^2 will be allowed to swing down lower and lower. A rearward swing of the lever T

to bring successively higher and higher portions of the eccentrically-curved part of the upper edge of the bar under the stud t^2 will then cause an upward swing of the plate S^2 until the concentric portion of the bar edge engages the stud. The teeth or projections t' on the upper edge of the bar will, as they ride under the stud t^2 , give a series of jars or shocks to the plate as the latter is being swung upward toward its most elevated position in which it is held without movement by the concentrically-curved plain portion of the bar edge when such portion is brought under the stud.

To provide for adjustment of the bar T' with reference to the arm of lever T carrying it, the forward end of the bar is fastened to the lever-arm by means of a screw t^3 , passing through a slot t^4 in such arm and tapped into the bar. About midway of its length said bar is provided with a pin t^5 , which projects through a slot t^6 in the lever-arm and engages the upper end of the plate t^7 , adjustably attached to the lever-arm by means of a screw t^8 , passing through a slot t^9 in the plate into said arm. With the construction described the bar can be adjusted to regulate the height or angle of its upper edge with reference to the lever-arm by loosening the screw t^3 , raising or lowering it in slot t^4 , and tightening it up again and by raising or lowering the adjustable plate t^7 .

As already described hereinbefore, the pins or abutments $g^2 g^3$ on the sliding bar G for striking and actuating the arm of the hopper-moving lever H are so situated that the lever will only be moved as the bar nears the upper and lower limits of its motion. As the bar nears its lowest position the upper of the two pins $g^2 g^3$ will strike the lever-arm, and, depressing it, will cause the lever to slide the hopper forward. Just as this forward movement of the hopper occurs the lever T has been moved by the described connections with the sliding bar G to bring the lowest part of bar T' under the stud t^2 on plate S^2 , and such plate has been allowed to swing down to bring its nose or outer-pointed end into its lowest position. As the hopper is moved forward, the end of the plate S^2 will then, riding over the bottoms of the slots $R^2 R^2$ in the hopper end and partition R' , be thrust into the mass of staples in the rear chamber of the hopper. The hopper then remains in its forward position until the bar G is raised again and approaches the upper limit of its motion and the plate S^2 , through the action of the lever T and bar T' , has been swung up into its elevated position with its upper edge in line with the top or upper edge of plate S . Pivoted in the bar S' above the edge of the staple receiving and guiding plate S is the lever U , having its forward lower end in position to rest upon the top of the next to the lowest one of a series of staples astride of the plate. A spring u in a suitable recess in the bar S' serves to press the end of the lever downward

into operative position. With this construction and with the magnet-bar of the hammer down, the lowest or first of a series of staples on the plate will rest against the side of the bar and the next one will have its top engaged by the end of the lever U. When the lowest or first staple is taken by the magnet-bar, as hereinafter described, the rest of the staples will, by the action of the holder-lever, be prevented from sliding down toward the magnet-bar way.

To cause the holder-lever to allow the staples to slide down to bring another one in contact with the magnet-bar when the latter has descended again, I provide the trip-lever V, having its lower end projecting slightly into the magnet-bar way near the lower end thereof, so as to be struck by the bar and moved outward as the latter reaches or nears its lowest position. The other end of this trip-lever is connected by means of link V' with the holder-lever U, so as to raise such lever from any staple on the plate S as the lower end of the trip-lever is engaged by the hammer magnet-bar.

To provide means for guiding a shoe-sole being stapled so that the staples will be driven in proper place, I employ a channel-guide W, having its end in line with the magnet-bar way. This guide is adapted to engage such a channel in the shoe-sole bottom as is usually made where the sole is to be stitched. As the sole is moved along to receive the successive staples it will then be guided so that such staples will be driven in proper line with reference to each other in the shoe-sole channel. The guide is preferably made adjustable, as shown, so that it can be properly adjusted to the depth of the channel in the sole. For this purpose it is formed on the lower end of a plate fitting in a vertical groove or way w in the plate containing the lower portion of the magnet-bar way. A screw w', engaging a slot w² in the plate or piece carrying the guide, serves to retain it in its groove. The upper end of the piece is, as shown, beveled or made inclined to engage the inclined under side of the cam-slide W', adapted to be moved horizontally as desired. The upper side of slide W' is horizontal and engages the horizontal upper side of the rabbet in which the slide is placed. A screw w³, engaging the slot w³ in the slide, serves to fasten the slide in place as adjusted. With this construction the channel-guide can be readily adjusted up or down and fixed as adjusted. Where it is to be lowered to project farther below the lower end of the hammer-bar guideway, the cam-slide can be moved out, so as to cam the guide-carrying piece down, and then fastened by its screw w².

I contemplate making the bar or plate K, in which the magnet-bar guideway is cut, in one piece from its top to its lower end; but in the drawings I have shown it, for convenience in assembling the parts, as made in two parts, the upper one held in place, as described herein-

before, by bolts L³ L³ and the lower one fastened by screws. The bottom of the front compartment is made, as shown in Fig. 9, inclined to one side, so that any staples falling into such compartment will slide down and out of the spout r when the gate r', closing the latter, is opened.

The operation of my machine, as shown and described, is, briefly, as follows: With magnet-bar of the hammer down and a number of staples on the inclined plate S', with the lowest or front staple against the magnet-bar I, and with a supply of staples in the hopper, the machine is ready to staple the sole of a shoe placed on the horn E. If now the treadle be pressed down to raise the treadle-rod, the horn will be raised with a yielding pressure to bring it up against the lower end of the magnet-bar-guiding head. The channel-guide meanwhile takes into the channel in the shoe-sole, so as to determine the position of the latter properly. As the treadle-rod and the vertically-sliding bar G connected therewith rise, the pawl or pawl-lever M, pivoted to the bar, raises the hammer-plunger against the stress of spring I⁴ by the engagement of its shoulder m with the under side of the arm on the plunger. Meantime, while the magnet-bar-carrying plunger is being raised to compress its spring the lever T, carrying bar T', is by its connection with bar G being swung rearward, causing the toothed portion of bar T' to ride under the stud t² on plate, so as to elevate the rear end of the plate. While the plate is being swung up it is given a series of sharp jars or shocks by the passage of the teeth on the bar edge, passing under the edge on the under side of stud t². The purpose of this is to settle any staples between which the nose of the plate has passed on penetrating the contents of the hopper squarely astride of the upper edge of the plate. Any that do not thus become properly seated on the plate will be jarred off as the upward swinging and jarring of the plate is continued. As already described herein-before, the nose of the plate, tapered down to a point, is caused to enter the mass of staples in the hopper while the plate is down by the forward motion of the hopper itself. To facilitate the entrance of the plate-nose between the legs of any of the staples coming in its way as it enters the hopper and to best secure the seating of such staples astride of the plate, it is not only cut away on an incline underneath, as described, but also preferably has its upper side or edge inclined or rounded a little upward and rearward above the line of the main part of the plate edge. The plate S² is by the continued movement of the lever T and bar T' swung up with a jarring motion until the plane concentric part of the upper edge of the bar T' comes into engagement with stud t². The plate is then tilted up at such an angle that the staples astride of its upper edge slide forward and downward onto the plate S, along which they slide down to

- those already in place thereon. Any staples picked up by the nose of plate S^2 in the hopper are kept from sliding down along the plate by the narrowness of the lower part of the slot R^2 in the hopper-partition until the plate has been swung up to raise it above the narrow and into the wide part of the slot. As the staples slide along down the plate any not seated squarely over the plate edge will be shaken or jarred off, so as to fall into the front compartment of the hopper, from which they can be taken through spout r , when desired, and returned to the other hopper-compartment. The upward incline of the rear end of the guide-bar S^3 , carried by the swinging plate, prevents any catching or clogging of the staples as they slide down the plate and assists to seat them properly on the edge of the plate. The function of the guide-bars S and S^2 in keeping the staples down on plates S and S^2 has been fully set forth hereinbefore. As the bar nears the end of its upward movement the lever H is struck and actuated by the lower pin or abutment g^2 , so as to slide the hopper rearward to bring the hopper-partition R' to the rear of the nose of the swinging picker S^2 . As the lower end of the magnet hammer-bar I^2 passes up out of contact with the end of trip-lever M the holding-lever U is forced down by its spring to engage the top of the staple next to the one resting against the magnet-bar. As the end of such bar passes the series of staples it attracts the loose end staple and draws it upward with its top in contact with the lower end of the magnet-bar. The bar way or groove then keeps the staple in proper upright position with its legs in line with the travel of the bar. The holder-lever U now keeps the remaining staples from sliding down on the plate S . As the bar G continues rising the pawl M is tripped by its incline m' engaging the trip-pin M^3 and the plunger carrying the hammer-bar is released to be driven by the force of the spring I^4 . This drives the staple held on the end of the magnet-bar into the shoe-sole. If the staple is of such length as to project through the sole, the inclined sides of the annular groove in the anvil E' on the horn E will turn the ends of the staple-legs so as to clinch them firmly.
- With the horn supported by a strong but yielding pressure, as described hereinbefore, the best clinching action is secured, as will be understood by those familiar with the riveting or clinching of metallic fasteners.
- With the horn supported by spring-pressure the machine can also be used for stapling shoes or other articles of different thicknesses without change or adjustment. As the bar G is being raised the pawl O' rises over the ratchet-teeth thereon in position to engage the teeth and prevent any downward movement of the bar until it has been given its full upward stroke to move the hammer-plunger and the other parts connected with the bar through their required motions. When
- the bar reaches the limit of its full upper stroke, the pawl is tripped and swung back, as described, by the cam-lug on the bar, so that the latter is free to descend again.
- The descent of the bar G first causes the lever T to be moved forward to allow the swinging picker S^2 to drop, so as to bring its nose down into its lowest position. The hopper-moving lever H is then actuated by engagement of the upper pin or abutment g^2 on the bar to move the hopper forward, causing the nose of the picker to pass through the lower end of the slot in the hopper-partition R' and penetrate into the mass of staples in the rear hopper-compartment. As the bar reaches its lowest position the pawl M is swung forward by its spring to bring its shoulder m under the arm I^2 on the hammer-plunger, and the pawl O' is, by the engagement of lug O^4 with the end of screw O^5 , shifted into position again to engage the ratchet-teeth on bar G when such bar is again being raised.
- To facilitate the drawing upward of the end or lowest staple on the staple-holder S by the end of the magnet-bar, I prefer to round the lower end of guide-bar S' or cut it away on an upward and forward incline. (See Figs. 6 and 16.) As the end of the magnet-bar attracts the top of the staple and draws it upward, this inclined or rounded end of the guide-bar will guide the staple over into the hammer-bar way to bring it squarely into line with bar.
- With my machine, as described, the stapling operation can be carried on continuously as long as there is a supply of staples in the hopper or receptacle. The staple-holder or guide for guiding the staples to the magnetic hammer-bar will always be kept supplied with staples by the staple picking and delivering devices described. The picker, operating as set forth each time that a staple is driven, will not fail to take from the hopper and deliver to the inclined holder enough staples to provide one for each driving movement of the hammer. If it should take up staples in excess of those needed to keep the holder supplied, those remaining on the picker as it descends will slide off of it and drop into the forward compartment of the hopper, to be taken therefrom and returned to the other compartment when required.
- Having thus described my invention, what I claim is—
1. In combination with a magnetic hammer-bar, a suitable piece or head having the way within which the hammer-bar is guided, adapted to guide and keep a tack in line with the movement of the bar, and extending below the point to which the lower end of the hammer-bar rises on its return stroke, and means for feeding a tack into position to be attracted by the hammer-bar before the latter finishes such stroke, substantially as and for the purpose specified.
  2. In combination with the moving magnetic hammer-bar, a head having a way for the hammer-bar, up within which the ham-

mer-bar on its return stroke rises, so as to carry its end above the lower end of the way, and means for feeding a tack into contact with the side of the bar, at a point below the 5 limit of the return travel of the bar end before the bar reaches the limit of its return stroke, substantially as and for the purpose set forth.

3. In combination with the reciprocating 10 hammer-bar of magnetic material, a head having a guiding-way for the bar, means for feeding a tack against the side of the bar, while it is down, and a suitable abutment to arrest such tack, as it travels up with the bar, and 15 cause it to pass underneath the end of the latter substantially as and for the purpose specified.

4. In combination with the rising and falling magnetic hammer-bar, a head having a 20 guiding-way for the bar, the guide adapted to receive staples or double-pointed tacks astride of its edge, and extending to a point beside the path of the hammer-bar below the 25 limit of the upward travel of the lower end of the bar, and a suitable abutment above the staple-guide, to arrest a staple as it travels up with the bar, and cause it to pass under the bar end, substantially as and for the purpose shown.

30 5. In combination with the hammer-bar and a head provided with a way for the bar, the inclined staple-holder adapted to receive the staples astride of its edge, and having its lower end at the side of the hammer-way, the 35 spring-pressed check-lever above such holder having its staple-engaging end so situated as to engage the staple next above one at the extreme lower end of the holder, a lever adapted to be actuated by the hammer-bar, 40 after it has passed below the staple-guide, and the link connecting such lever with the check-lever, substantially as and for the purpose set forth.

6. As an improvement in means for taking 45 staples from a receptacle, a swinging piece having a pointed nose adapted to be thrust into a mass of staples in the receptacle, and to pass between the legs of such of the staples as come in its way, in combination with 50 means for giving the piece a series of jars or shocks and swinging it upward, substantially as and for the purpose described.

7. As a means for taking staples from a mass and arranging them right side up, ready 55 for use, a swinging plate having its upper edge adapted to receive the staples astride of it, and provided with the pointed end adapted to be thrust into the mass of staples, in combination with mechanism for jarring the plate, 60 while swinging it upward, substantially as and for the purpose specified.

8. As a means for taking staples from a mass in a suitable receptacle, the swinging 65 plate of a thickness substantially equal to or less than the distance between the legs of one of the staples and having a pointed nose adapted to enter the mass of staples, and

mechanism for dropping the plate, so that its nose enters the mass of staples in a downwardly-inclined position, and then raising the 70 plate with a series of shocks, substantially as and for the purpose shown.

9. As a means for taking staples from a mass in a suitable receptacle, in combination with a swinging piece adapted to receive staples astride of it, and having a pointed nose adapted to enter between the legs of some of the staples, as it penetrates the mass, means for swinging the piece upward with a series of shocks, and a suitable guide to keep the 80 staples in place, as they slide down the edge of the piece, when the latter reaches its elevated inclined position, substantially as and for the purpose set forth.

10. In combination with the swinging picker, 85 having the end adapted to penetrate a mass of staples and having a lug, a bar having a curved edge provided with a series of teeth or projections adapted to engage the lug on the picker, as the bar is moved, and means for 90 actuating the bar, substantially as and for the purpose described.

11. In combination with the swinging picker provided with a lug and having its end adapted to penetrate a mass of staples in a suitable 95 receptacle, a moving bar engaging with its edge the lug or stud on the picker, and having its edge shaped to swing the picker upward as the bar is moved, and provided with a series of teeth, substantially as and for the purpose shown.

12. In combination with the swinging picker provided with the stud or lug, a swinging lever carrying a bar, having its upper edge in position to engage the stud on the picker, 105 curved to swing the picker upward as the bar is moved, and provided with a series of teeth or projections, substantially as and for the purpose specified.

13. In combination with the swinging picker 110 provided with the stud or lug, the swinging lever and the bar on the lever having a portion of its upper edge in position to engage the stud on the picker, curved eccentrically and provided with teeth or projections substantially as and for the purpose set forth.

14. In combination with the swinging picker, the lever, the bar or piece on such lever having part of its edge curved eccentrically with reference to the swing of the lever, and provided with teeth, and the rest of its edge curved concentrically and made plain, and a suitable stud or lug on the picker to engage the bar edge, substantially as and for the purpose described.

15. In combination with the picker having the pointed nose to penetrate a mass of staples, and its upper edge adapted to receive staples astride of it, a lug or stud on the picker, the swinging lever carrying the bar or piece having a portion of its edge curved eccentrically with reference to the swing of the lever, and provided with teeth with inclined sides, and the other portion of its edge plain and curved

concentrically, substantially as and for the purpose specified.

16. As a means for taking staples from a mass, the picker having a thickness substantially equal to or less than the width of the space between the legs of one of the staples, and its end cut away beneath to form a pointed nose, in combination with a guide above the upper edge of the picker-body, having its outer end turned upward, substantially as and for the purpose shown.

17. As a means for taking staples from a mass, the picker consisting of a swinging plate having its upper edge of a thickness substantially equal to or less than the width between the legs of one of the staples, and its end formed into a pointed nose with its upper edge inclined upward at an angle to the upper edge of the plate-body, substantially as and for the purpose set forth.

18. In combination with the swinging picker, provided with a lug, the swinging lever and bar carried thereby, having the curved edge for engaging the lug on the picker, adjustably supported on the lever, substantially as and for the purpose described.

19. In combination with the lever and bar carried thereby, the screw passing through a slot in the bar and into the end of the bar a pin or lug, the bar entering a slot in the lever, and an adjustable plate on the lever engaging the pin, substantially as and for the purpose specified.

20. As a means for taking staples from a mass and delivering them in proper position for use, in combination with the inclined holder and guide, adapted to receive staples astride of its upper edge, the swinging picker for taking the staples from a suitable receptacle, and means for swinging the picker up with a jarring action, until its upper staple-supporting edge is in line with and forms a continuation of the edge of the holder, substantially as and for the purpose described.

21. In combination with the staple-holder and guide with the upper inclined edge adapted to receive staples astride of it, the swinging picker having the pointed nose to penetrate a mass of staples, and a lug or stud, the swinging lever and the bar thereon having a portion of its upper edge plain and curved concentrically and the other part toothed and curved eccentrically downward, substantially as and for the purpose specified.

22. In combination with the swinging picker and means for swinging it up and down, a hopper for the staples having a slot for the admission of the nose of the picker, and means for moving the hopper toward the picker, when the latter is down, and moving it away again when the picker has been raised, substantially as and for the purpose shown.

23. In combination with the rising and falling picker, having a pointed nose adapted to enter a mass of staples and pass between the legs of any coming properly in its way, a hopper for receiving the staples, having, in the

wall of its staple-holding compartment, a slot to admit the passage and upward swing of the picker, and means for moving the hopper toward and from the picker, when the latter is down and up, respectively, substantially as and for the purpose set forth.

24. In combination with the rising and falling picker, the hopper having, in the side of its staple-containing compartment, a slot to admit the picker end, such slot having its lower portion narrow and its upper portion wider than one of the staples, and means for moving the hopper toward and from the picker, substantially as and for the purpose described.

25. In combination with the rising and falling picker, and means for swinging it up with a jarring motion, the hopper having the two compartments, the rear or outer one containing the staples and having a slot for admission of the picker in the partition between the compartments, with its lower portion narrower and its upper portion wider than one of the staples, and means for moving the hopper toward the picker when the latter is down, and away from it when it has been swung up, substantially as and for the purpose specified.

26. In combination with the movable hopper having the two compartments, the outer one to contain the staples, and the partition between the compartments provided with a slot with its lower portion narrower and its upper portion wider than one of the staples, the swinging picker having the nose adapted to penetrate the mass of staples in the hopper, and means for swinging the picker up with a jarring motion until it is in an inclined position and above the narrow portion of the slot in the hopper, substantially as and for the purpose shown.

27. In combination with the swinging picker provided with a nose to enter a mass of staples, and a stud or lug, the movable hopper having a slot for admission of the picker, the swinging lever and curved bar carried thereby having the concentric plane and eccentric toothed portions, to engage the stud or lug on the picker, substantially as and for the purpose set forth.

28. In combination with the sliding bar for actuating the parts of the machine, the lever carrying the picker-operating bar, the movable hopper, the lever for moving the same, and connections between the two levers and the sliding bar, substantially as and for the purpose described.

29. In combination with the swinging picker and the movable hopper or receptacle, the sliding bar, the lever carrying the picker-actuating device, the pin on the bar engaging a fork in the lever, the hopper-moving lever, and the pins or studs on the sliding bar adapted to strike and move an arm on the latter lever, substantially as and for the purpose specified.

30. In combination with the swinging picker and the movable hopper, the sliding bar and means for moving it, the lever carrying the

- device for swinging the picker connected with the bar, so as to move therewith, the hopper-moving lever, and suitable studs or abutments on the sliding bar, to engage and operate such latter lever only as the bar approaches the opposite ends of its movement, substantially as and for the purpose shown.
31. In a tack-driving machine, in combination with a movable piece or bar for actuating the operative parts of the machine, means for insuring a full movement of such bar or piece in one direction before its return, substantially as and for the purpose set forth.
32. In a tack-driving machine, in combination with a movable piece or bar, for actuating the operative parts of the machine, provided with one or more teeth, a pawl to engage the latter, and means moved by the piece or bar to move the pawl out of operative position, substantially as and for the purpose shown.
33. In a tack-driving machine, in combination with the moving piece or bar, for actuating the operative parts of the machine, having one or more teeth, the pawl to engage the latter, and means carried by the piece or bar, to move the pawl into and out of position to engage the teeth, substantially as and for the purpose described.
34. In a tack-driving machine, in combination with the moving piece or bar, for actuating the operative parts of the machine, means for insuring a full movement of such piece or bar, the hammer-bar connections between the latter and the actuating-piece and means for tripping such connections only at or near the limit of the movement of the actuating-piece, substantially as and for the purpose specified.
35. In a tack-driving machine, in combination with the hammer-bar carrying a lug, the moving piece or bar, a pawl on the latter engaging the hammer-bar lug, means for tripping the pawl, as the moving piece or bar approaches the limit of its motion, and means for insuring the full movement of such piece or bar, substantially as and for the purpose shown.
36. In a tack-driving machine, in combination with the hammer the moving piece or bar having an arm, trip connections between such piece and the hammer-bar, whereby the latter is raised and then released, as the moving piece rises, the movable work-support, a collar on the support, and a spring interposed between the arm on the movable piece and such collar, substantially as and for the purpose specified.
37. In a tack-driving machine, in combination with a movable piece or bar for actuating the operative parts of the machine, and a suitable treadle or other mechanism connected with the bar, so as to move it, means for locking the bar against return, until it has completed its movement to actuate the machine parts, consisting of a series of

ratchet-teeth on the bar, and a pawl to engage such teeth, substantially as and for the purpose set forth.

38. In a tack-driving machine, in combination with the movable piece for actuating the different parts of the machine, the means for insuring full movement of the piece in one direction before return, consisting of a series of ratchet-teeth on the piece, a pawl to engage such teeth, and a tripping device on the piece, to trip the pawl, as the piece reaches the limit of its motion, substantially as and for the purpose described.

39. In a tack-driving machine in combination with the reciprocating bar, for actuating parts of the machine, ratchet-teeth on the bar, the pawl for engaging such teeth, means for holding the pawl as swung into and out of position to engage the ratchet-teeth, and a trip-lug on the bar, to swing the pawl out of and into its engaging position, at opposite ends of the bar's travel, substantially as and for the purpose shown.

40. In combination with the sliding bar provided with ratchet-teeth, the pawl, the spring engaging the pawl, so as to hold the same as swung into and out of position to engage the ratchet, a lug on the bar adapted to trip the pawl outward, as the bar reaches the upward limit of its motion, and a suitable arm or stop on the pawl to be engaged by the lug on the bar, as said bar reaches its lowest position, so as to swing the pawl into engaging position again, substantially as and for the purpose set forth.

41. In a tack-driving machine, in combination with the treadle and the sliding bar connected therewith, for actuating the driving mechanism, the ratchet-teeth and the lug on the bar, the pawl on the frame, for engaging the ratchet-teeth, provided with a suitable abutment, to be engaged by the under side of the lug on the bar, and the spring engaging a part of the pawl, so as to tend to hold it as swung either into or out of position to engage the teeth on the bar, substantially as and for the purpose described.

42. In a tack-driving machine, in combination with the actuating-bar, the treadle connected therewith, and a spring acting to force the treadle and bar down, when raised, and means substantially as described, for locking the bar against any downward movement, until it has made a full upward movement, substantially as and for the purpose specified.

43. In combination with the hammer-head-carrying plunger, provided with an upwardly-projecting guide-stem, the guide-frame provided with means for guiding such stem, and with a vertical slot through which projects an arm on the plunger, a sliding bar, the pawl pivoted to the bar, and having a shoulder to engage the plunger-arm, and a cam or incline, a guide on the guide-frame through which the upper end of the pawl passes, a spring en-

gaging the pawl, and the pin or abutment for engaging the incline on the pawl, substantially as and for the purpose set forth.

44. In a tack-driving machine for boots and shoes, in combination with the hammer-bar and a suitable head having the way down which the bar carries the tacks, a channel-guide extending down from the head below the end of the way therein and having a portion to engage the channel in the boot or shoe sole, so as to bring such channel directly under the hammer-bar, and any staple driven down thereby, substantially as and for the purpose described.

45. In a machine for driving tacks in the soles of boots and shoes, in combination with the head carrying the driving devices, a channel-guide on such head having a projecting portion for engaging the channel in the sole and guiding the same under the tack-driving devices, made adjustable in height, with reference to the head, to suit it for channels of different depths, substantially as and for the purpose specified.

46. In a tack-driving machine, in combination with the head containing the way for guiding the hammer-bar, the channel-guide on a plate held and guided in a vertical way or recess, the adjusting-plate having the inclined lower edge engaging the inclined upper edge of the plate carrying the channel-guide,

and means for fixing the adjusting-plate in any desired position, substantially as and for the purpose shown.

47. In a machine for driving tacks in soles of boots and shoes, in combination with the support, for receiving and supporting the boot or shoe, the shank of the support held in suitable guides so as to be movable up and down, the treadle-rod provided with a fork, the sliding collar on the support-shank, engaged by such fork, the spring on the shank above the collar, and a fixed collar or abutment on the shank engaged by the upper end of the spring, substantially as and for the purpose set forth.

48. In a tack-driving machine, in combination with the magnetic hammer-bar guided in a suitable way, an abutment at the side of the path of the hammer-bar having a face inclined upward and inwardly toward the hammer-bar way, so as to arrest any tack clinging to the side of the hammer-bar as the latter rises, and guide it under the bar end, substantially as and for the purpose specified.

In testimony that I claim the foregoing I have hereunto set my hand this 30th day of June, 1888.
